Specification for Design.

Patented May 4, 1920.

Application filed February 14, 1920. Serial No. 358,667. Term of patent 3½ years.

To all whom it may concern:

Be it known that I, ALBERT F. SAUNDERS, a citizen of the United States, residing at 106 Rugby road, city of Syracuse, county of Onondaga, and State of New York, have invented a new, original, and ornamental Design for a Sundae-Holder, of which the following is a specification, reference being had to the accompanying drawing, forming a part thereof, wherein—

Fig. 2 is a side elevation of the sundae holder.

I claim:

The ornamental design for a sundae holder, substantially as shown.

In testimony whereof, I have hereunto signed my name at East Syracuse, in the county of Onondaga and State of New York, this 10th day of February, 1920.

ALBERT F. SAUNDERS.
